ABSTRACT OF THE DISCLOSURE

Freestanding shelving comprises uprights having feet at their lower ends to support the assembly in a vertical plane. Adjacent uprights are connected and spaced apart by cross members provided with end plates formed with hook-shaped portions adapted to engage in slots in the uprights. Plate like shelf brackets have hook-like portions for engaging other slots in the uprights and in position extend at right angles to the cross members. Strips secured by one edge to the shelf brackets form pockets to receive side flanges of shelves to support such shelves between pairs of brackets. An arrangement of spaced flanges at the front edge of a shelf defines a space to accommodate an extruded plastics section to which a label may be affixed.

SUMMARY OF THE INVENTION

This invention relates to shelving.

An object of the invention is to provide shelving which can be readily assembled and dismantled and adapted to suit various requirements. The invention lends itself to the provision of temporary storage means in a variety of arrangements and can be adapted, for instance, in libraries to arrangements of rows of shelving or to study bays each storing books on a particular subject and leaving a space for desks or tables for use by readers.

In accordance with the invention there is provided freestanding shelving wherein the improvement comprises a plurality of uprights, a foot at the lower end of each upright for supporting the assembly at least in one vertical plane, cross members for extending transversely of said vertical plane and for spacing apart the uprights, shelf brackets for extending parallel to said vertical plane and shelves for detachable attachment to the shelf brackets, each cross member having attachment means on the opposite ends thereof for detachable attachment to co-operable means at different heights on the uprights, each shelf bracket having attachment means on the inner end thereof for detachable attachment to co-operable means at different heights on the uprights.

BRIEF DESCRIPTION OF THE DRAWINGS

In the attached drawings, which illustrate a preferred embodiment of the invention:

FIGURE 1 is a front view partly in section, of shelving embodying the invention and shows one upright together with the cross members, shelf brackets and shelves detachably attached thereto;

FIGURE 2 is an end view of the shelving of FIGURE 1; and

FIGURE 3 illustrates the way in which the shelf brackets and shelves are attached to one another and to the upright.

DESCRIPTION OF PREFERRED EMBODIMENT

In illustrating exemplary shelving in the drawings only one of a number of identical interconnected uprights has been shown, since this is sufficient to describe the putting into effect of the invention.

2

Referring to the drawings, each upright 1 comprises a tubular body 2 of circular cross-section provided with four sets of rectangular slots 3 extending lengthwise of such tubular body. The four sets of slots 3 are spaced at 90° intervals about the tubular body 2. Two feet 4 extend transversely from the bottom of the upright 1 in a plane passing through two opposite sets of slots 3. Adjustable sole pieces 5 are provided at the outer ends of the feet 4.

5 Cross members 6 serve to interconnect adjacent uprights 1 and thereby space the uprights apart. Each cross member 6 comprises a tube 7 of rectangular section. At each end of the tube 7 a plate 8 is fitted in slots extending longitudinally in two opposite sides of the tube 7 and is welded to the tube. Each plate 8 extends laterally beyond the opposite sides of the tube 7 and is provided with hook-shaped extensions 9 which project beyond the end of the tube 7. The hook-shaped extensions 9 are so shaped that they can be inserted in slots 3 in the upright 1 which lie in a plane at right angles to the plane containing the feet 4 and then lowered so that downwardly-opening notches 10 in the extensions 9 engage over the bottom edge 11 of the slots 13 to provide a locking action and maintain the assembly rigid.

10 25 Each shelf bracket 15 is in the form of a rectangular plate 16 having hook-like extensions 17 similar to those on the cross-member 6 on the inner end for co-operation with slots 3 in the upright 1 lying in the plane containing the feet 4. At least one elongated open-ended pocket 18 is provided on each side of the plate 16 to open upwardly by spot-welding the lower edge of a suitably sectioned strip 19 to the plate 16.

15 30 35 Each shelf 20 is formed from a generally rectangular plate 21 having a downwardly extending flange 22 at each side to fit into a pocket 18 on a shelf bracket 15. The side flanges 22 extend across most of the width of the shelf 20. The side flanges 22 are each provided with a central cut-out (not shown) dividing the flange into two parts having convex free edges in order to minimize any tilting of the shelf 20 when supported between two shelf brackets 15 by virtue of manufacturing tolerances.

35 40 45 50 55 60 65 70 Each shelf 20 is formed from a generally rectangular plate 21 having a downwardly extending flange 22 at each side to fit into a pocket 18 on a shelf bracket 15. The side flanges 22 extend across most of the width of the shelf 20. The side flanges 22 are each provided with a central cut-out (not shown) dividing the flange into two parts having convex free edges in order to minimize any tilting of the shelf 20 when supported between two shelf brackets 15 by virtue of manufacturing tolerances.

The rear and front edges of the shelf 20 are reinforced and for this purpose at the rear of the shelf a downwardly extending flange (not shown) is provided along the whole length of the shelf. The end flanges of a right-angled, M-sectioned strengthening member (not shown) are spot-welded respectively to the front side of the rear flange and the under-surface of the plate 21. At the front of the shelf 20 a shallow downwardly extending flange 25 extends along the whole length of the shelf 20 and a right-angled, U-sectioned strengthening member 26 has its flanges 27 extending rearwardly with one flange spot-welded to the under-surface of the plate 21. The centre portion 28 of the front strengthening member 26 extending between the flanges 27 is spaced behind the shallow flange 25 on the front of the plate 21 and the other flange of the member 26 is spot-welded to a rearwardly-extending flange 29 of an L-section strip 30 having a remaining shallow flange 31 extending upwardly spaced in front of the web 28 of the member 26 and under the front flange 25 of the plate 21 but spaced therefrom. The space between the portion 28 of the member 26 and the flanges 25 and 31 accommodates an extruded plastics section 32 to which can be affixed a label carrying indicia visible between the flanges 25 and 31.

A basic shelving unit is made up of two uprights 1 with two cross members 6 interconnecting them at different heights and extending transversely of the feet 4 on the uprights, shelf brackets 15 and shelves 20 being added as required. Such a unit will stand safely because

3

the adjustable sole pieces 5 on the feet will occupy the four corners of a rectangle. The depths of the shelves 20 can vary to suit requirements and with extra deep shelves extra long feet 4 are provided on the uprights. The cross members 6 can also be made in a number of standard lengths as required.

Where a shelving bay is to be provided two such basic shelving units may be disposed opposite and parallel with each other and extra cross members may interconnect two opposite uprights via some of the slots otherwise provided for the shelf brackets.

We claim:

1. Freestanding shelving wherein the improvement comprises a plurality of uprights, a foot at the lower end of each upright supporting the assembly at least in one vertical plane, cross members spacing apart the uprights, shelf brackets extending parallel to said vertical plane and shelves, the shelf bracket being detachably attached to the shelves, each upright comprising longitudinally extending slots receiving hook-like extensions on the shelf brackets, each shelf bracket having at least one elongated, upwardly-opening pocket on each side thereof, each pocket receiving a complementary flange on a shelf, each cross member having attachment means on the opposite ends thereof detachably attached to co-operable means at different heights on the uprights, each shelf bracket having attachment means on the inner end thereof detachably attached to co-operable means at different heights on the uprights.

10

20

25

4

2. Shelving according to claim 1, in which each upright comprises longitudinally extending slots receiving hook-shaped portions formed at the opposite ends of cross members.

3. Shelving according to claim 2, in which each cross member comprises a tube of rectangular cross-section having attached to each end a plate formed with the said hook-shaped portions.

4. Shelving according to claim 1, in which each shelf bracket comprises a plate and each pocket is formed by a strip attached to the plate along a lower edge of such strip, the strip having an upper portion spaced from the plate.

5. Shelving according to claim 4, in which spaced flanges disposed at the front edge of a shelf define a space adapted to accommodate an extruded plastics section to which a label may be affixed.
